UNITED STATES PATENT OFFICE.

CARLO PRADA, OF MILAN, ITALY.

ELECTRIC SWITCH.

1,387,865.

Specification of Letters Patent. Patented Aug. 16, 1921.

Application filed August 13, 1919. Serial No. 317,115.

To all whom it may concern:

Be it known that I, CARLO PRADA, manufacturer, a subject of the Kingdom of Italy, and resident of Milan, Via Bramante 22, 5 Italy, have invented certain new and useful Improvements in and Relating to Electric Switches, of which the following is a specification.

The present invention relates to an improved electric switch of the type in which a push button acts on a rotary member to open and close the contacts of an electric circuit.

The object of the invention is to provide 15 a switch embodying security of function and simplicity of construction.

The invention will be better understood with reference to the annexed drawings in which:

20 Figure 1 is a sectional view of a bipolar switch showing the circuit broken.

Fig. 2 is a plan view of the device, some of the parts being omitted.

Fig. 3 is a view similar to Fig. 1, but 25 showing the circuit closed.

Figs. 4 and 5 represent two different views of the rotary member of the switch.

Figs. 6 and 7 are two different views of a driving member of the switch.

30 The switch mechanism is mounted on the base —1— of insulating material and is protected by cover —2— provided with a central hole —3— through which the driving spindle projects.

35 The switch mechanism comprises a metallic frame —4— bearing a rotary member which consists of a quadrangular prism —5— provided with contact projections —6—. —7— is a plate spring to snap said

40 rotary member and fastened on base —4—. —8— are contact spring plates fitted in front of projections —6— and fastened by their lower ends —9— in recesses of base —1— by means of bolts —11—; —12— and

45 —13— being nuts fitted on said bolts to form the terminals whereon are joined the line ends.

The switch mechanism is operated by means of a spindle —14— fitted and guided 50 in frame —4— and provided with a spiral return spring —15— acting between the base of frame —4— and an enlargement

—14'— of said spindle. —16— is an angular bracket fitted between the push-button —17— and enlargement —14'— said bracket 55 having its depending arm provided with fingers —18— and —19—.

The outer fingers —18— act eccentrically on rotary member —5— while finger —19— constantly presses against said rotary 60 member thereby coacting with plate spring —7— to keep it registered.

A pressure being exercised on button —17— the rotary member revolves $\frac{1}{4}$ turn and snaps on spring —7—; —20— is a stop 65 pin for spindle —14—.

The circuit between terminals (12—13) is formed through bolts —11—, plates —8— projections 6 and member —5—.

The circuit closes at every half turn, at 70 every two pulsations of button —17—.

I claim:

1. An electric switch, comprising a casing, contact members therein, a rotary make and break device comprising a reduced body 75 portion and enlarged end portions, a push button spindle reciprocable in the casing, and means carried by the spindle for moving said make and break device into and out of contact with said contact members, said 80 means having a portion which engages one part of said make and break device to rotate it and another portion to keep it properly registered.

2. An electric switch, comprising a cas- 85 ing, contact members therein, a rotary make and break device, comprising a reduced body portion and enlarged end portions, a push button spindle reciprocable in the casing, and an angular bracket carried by said spin- 90 dle and having fingers projecting therefrom at different planes for simultaneously engaging different parts of said make and break device, the fingers of one plane serving to move the make and break device into and 95 out of engagement with said contact members and the other fingers serving to keep the make and break device in proper register.

In testimony whereof I affixed my signature, in presence of two witnesses.

CARLO PRADA.

Witnesses:
